UNITED STATES PATENT OFFICE.

CHARLES W. CLARK, OF ARDMORE, PENNSYLVANIA.

DESIGN FOR A CHAIR.

SPECIFICATION forming part of Design No. 35,779, dated February 25, 1902.

Application filed January 29, 1902. Serial No. 91,810. Term of patent 3½ years.

To all whom it may concern:

Be it known that I, CHARLES W. CLARK, a citizen of the United States, residing at Ardmore, county of Montgomery, State of Pennsylvania, have invented and produced a new and original Design for a Chair, of which the following is a specification, reference being had to the accompanying drawings, forming a part thereof.

10 The leading features of my design for a chair are the sides thereof simulating the bowls and stems of smoking-pipes.

Figure 1 represents a perspective view of a chair embodying my design. Fig. 2 represents a front view thereof.

15 Referring to the drawings, A designates a chair, consisting of the sides B B, the seat C,

and the back D. The sides each simulate the bowl E and stem F of a tobacco or smoking pipe and are flat in their vertical direction. 20 On the sides of upper ends of the main portions of the bowls E are simulations of cavities or openings G in said bowls. Projecting from the rear of the bases of the bowls are feet H. 25

Having described my invention, what I claim as new, and desire to secure by Letters Patent, is—

The design for a chair substantially as shown and described.

CHARLES W. CLARK.
